FUEL FEED BURNER

Harry S. Lee, Detroit, Mich.

Application June 23, 1932, Serial No. 618,836

8 Claims. (Cl. 110—104)

My invention relates to improvements in a fuel feed burner particularly adapted for use with cement clinker kilns and is shown as embodied in a burner adapted to feed powdered fuel to a rotary cement kiln, though the invention is obviously adaptable to any suitable type burner appliance of the same general character.

An object is to provide a fuel feed burner capable of feeding powdered fuel into a cement kiln and adapted to create and maintain a controlled combustion capable of being directed as desired into the cement kiln.

Another object is the provision of a fuel feed burner capable of delivering powdered fuel in an air stream into a combustion zone supplied with air heated to produce combustion substantially upon contact with the fuel and wherein the heated air is caused to pass into a combustion zone over the discharge pipe for the powdered fuel and wherein such fuel discharge pipe is capable of adjustable positioning with respect to such combustion zone.

Another object is to provide an insulating layer of cooling air constantly passed over the fuel feed pipe to protect the same from heated air in the combustion zone whereby pre-ignition of the fuel in the said pipe is prevented.

Another object is the provision of a burner of this type wherein there is provided a fuel feed pipe and an encircling outer air pipe. The feed pipe communicates with a suitable source of powdered fuel and the air pipe communicates with a suitable supply of air. These pipes are telescopically arranged and one of the pipes is longitudinally adjustable with respect to the other so that the discharge ends of the pipes may be varied with respect to each other. In the particular embodiment illustrated in Figs. 1 and 2 both pipes pass through the wall of an enclosure which forms an insulated combustion chamber about the pipes and into which they discharge and wherein combustion commences, which chamber itself discharges into a cement kiln. The two pipes are angularly adjustable as a unit within said chamber and the outer pipe provides an air passageway about the inner pipe protectively insulating the same from the heated air blast driven through the chamber from another source. The outer pipe is adjustable lengthwise with respect to the inner pipe and is provided with a valve to control the admission of air therethrough.

Other objects and meritorious features of my invention will more fully appear from the fol-

lowing description, appended claims, and accompanying drawings, wherein:

Fig. 1 is a side elevation partly broken away showing my invention embodied in cement manufacturing apparatus,

Fig. 2 is an enlarged sectional view through my improved burner,

Fig. 3 is a sectional view taken on line 3—3 of Fig. 2.

In the assembly view shown in Fig. 1, 10 indicates a conventional rotary cement kiln except for the improvement represented in my instant invention. The construction of Fig. 1 is generally similar to that illustrated in my application Ser. No. 592,774, filed February 13, 1932, 15 Cement forming aggregate is deposited into the rotary kiln 10 to flow therethrough toward the discharge end of the kiln, the kiln being supported and operated for this purpose. The clinker following its passage through the kiln is discharged through a vertical passageway 12 into a cooling chamber indicated generally as 14. A drag chain 16 is arranged to travel through the cooling chamber to move the cement clinker along at a predetermined desired rate and this 25 chamber is separated by gates 18, 20, and 22 into a plurality of compartments wherein certain desired operations occur as set forth in the application Ser. No. 592,774. These operations form no necessary part of this invention. Air is 30 directed through the grate over which the drag chain travels and through the drag chain into the compartments from a plurality of air discharge outlets 24 and this air, after passing through the clinker and performing its desired function, is 35 discharged from the forward compartment through passageway 26. It is discharged from the rear compartment through passageway 28.

Air is also taken from a jacketed portion 29 surrounding the chamber 14, as shown in the co-pending application Serial No. 592,774, through an air conduit 30 to a blower 32. The blower is adapted to direct the air through the fuel feed pipe 34 as a direct feed for the fuel which is discharged into the pipe through a spout 36 which 45 communicates therewith as shown in Fig. 1.

The air which is discharged through the passageway 26 has passed through the heated clinkers on the drag chain and is therefore very highly heated air. This air enters the enclosure 38 which 50 surrounds the discharge end of the fuel feed pipe and within this enclosure or, as it is termed in the trade, "bustle" it picks up the powdered fuel and the fuel and air enter the kiln. The sources of air for the blower and for the passageway 26 are 55

shown as originating in the cooling chamber 14. These sources of air form no necessary part of this invention and it is obvious that other sources of air for the fuel feed mechanism could be satisfactorily used.

- My invention is directed to the fuel feed apparatus and it will be noted that the enclosure 38 is lined with suitable refractory material 40 and discharges directly into the open end of the kiln.
- 10 The air pipe 26 discharges from one side into the enclosure opposite the fuel feed pipe. The fuel feed pipe shown in Fig. 1 is provided with a plurality of joints 42 which permit angular adjustment of the pipe. The fuel feed pipe passes through the wall of the enclosure 38 as shown in detail particularly in Fig. 2, and at its discharge end is provided with a series of deflectors 44 adapted to set up swirls in the powdered fuel stream being blown through the pipe.
- 15 20 The fuel feed pipe is surrounded by a secondary air pipe 46 spaced therefrom to provide an air passageway open to the atmosphere at 48 through which an air stream is drawn which insulates the fuel feed pipe from the direct attack of the heated air entering the enclosure through the air pipe 26. The air which enters through the pipe 26 is very highly heated, that is, heated to a point where combustion occurs substantially instantaneously upon the air striking the fuel feed stream. The secondary pipe 46 therefore serves to insulate the fuel feed pipe so that pre-ignition of the fuel will not occur within the fuel feed pipe. This secondary pipe is slidably adjustable through the wall of the enclosure so as to vary the relative position of the discharge end of the secondary pipe with respect to the discharge end of the fuel feed pipe. A threaded adjustment 50 is shown which is operable to accomplish this function. A valve member 52 has a sleeve portion 54 which encircles the fuel feed pipe 34 as shown in Fig. 2 and the sleeve portion is provided with an angularly extending slot 56 within which is positioned a pin 58 carried by the fuel feed pipe so that rotation of this sleeve valve element moves the radially extending portion 52 of the valve toward or away from the open end 48 of the secondary air pipe 46 and thereby controls the amount of air permitted to enter the pipe 46.
- 25 30 35 40 45 50 55 60 65 70 75 A support is provided for the fuel feed pipe and the secondary air pipe in the form of a bracket 60 secured by bolts 62 to the end of the enclosure. The bolts 62 have play through the end of the enclosure and there are provided two tapered rings 64 and 66 which are arranged between the bracket or ring 60 and the end of the enclosure and which upon rotation tilt the tubular extension 61 of the ring or bracket 60 and through this tilting tilt the feed pipe 34 and the secondary air pipe 46 as shown in Fig. 1 so that the fuel blast may be directed as desired to the kiln. This tilting is for the purpose of directing the fuel blast as desired into the kiln.

I claim:

1. Fuel feed mechanism for a cement kiln comprising, in combination with a kiln, a fuel feed pipe arranged to direct a stream of powdered fuel into the kiln, a source of heated air, an enclosure surrounding the discharge end of said fuel feed pipe forming a chamber thereabout communicating with the source of heated air to receive air therefrom to pass through said chamber over the discharge end of the fuel feed pipe into the kiln, an air pipe extending through the wall of the enclosure telescopically surrounding the fuel feed pipe but spaced therefrom forming an air passageway therearound insulating the fuel feed pipe from the

5 10 15 20 25 30 35 40 45 50 55 60 65 70 75 an air passageway therearound, and means supporting said pipes operable to adjust the angular position thereof as a unit within the enclosure.

2. Fuel feed mechanism for a cement kiln comprising, in combination with a kiln, a fuel feed pipe arranged to direct a stream of powdered fuel into the kiln, a source of heated air, an enclosure open at one end to the kiln surrounding the discharge end of said fuel feed pipe forming a chamber thereabout communicating with the source of heated air to receive air therefrom to pass through said chamber over the discharge end of the fuel feed pipe into the kiln, an air pipe extending through the wall of the enclosure telescopically surrounding the fuel feed pipe but spaced therefrom forming an air passageway therearound, means supporting said pipes operable to adjust the angular position thereof as a unit within the enclosure, and means coupled with one of said pipes and operable to move the same endwise with respect to the other pipe.

3. Fuel feed mechanism for a cement kiln comprising, in combination with a kiln, a fuel feed pipe arranged to direct a stream of powdered fuel into the kiln, a source of heated air, an enclosure open at one end to the kiln surrounding the discharge end of said fuel feed pipe forming a chamber thereabout communicating with the source of heated air to receive air therefrom to pass through said chamber over the discharge end of the fuel feed pipe into the kiln, an air pipe extending through the wall of the enclosure telescopically surrounding the fuel feed pipe but spaced therefrom forming an air passageway therearound, means supporting said pipes operable to adjust the angular position thereof as a unit within the enclosure, and means controlling the admission of air into said air pipe, and means engaging said air pipe operable to advance or withdraw the same with respect to the said fuel feed pipe.

4. In combination, a cement kiln, an enclosure forming a chamber communicating at one end with one end of the kiln, a fuel feed pipe extending through said enclosure adapted to discharge into the kiln, an air pipe of larger diameter than the fuel feed pipe extending through said enclosure surrounding the fuel feed pipe in spaced relationship therewith, a source of heated air, means for delivering heated air from said source into said enclosure forward of the discharge end of the fuel feed pipe and air pipe, means supporting said fuel feed pipe and air pipe operable to adjustably tilt said pipes as a unit within said enclosure, said air pipe communicating with the atmosphere at one end to receive air therefrom and communicating with the kiln at the opposite end to discharge air thereinto and forming an air space about the fuel feed pipe insulating the same from the heated air within the chamber.

5. In combination with a cement kiln and a source of heated air fuel feed mechanism comprising a fuel feed pipe adapted to direct a stream of fuel into the kiln, an enclosure surrounding the discharge end of said fuel feed pipe forming a chamber thereabout communicating at one end with the kiln and communicating with the source of heated air to receive air from said source to pass through the chamber over the discharge end of the fuel feed pipe into the kiln, an air pipe extending through the wall of the enclosure telescopically surrounding the fuel feed pipe but spaced therefrom forming an air passageway therearound insulating the fuel feed pipe from the

heated air within the chamber, means supporting said pipes operable to adjust the angular position thereof as a unit within the enclosure.

6. Fuel feed mechanism for discharging fuel into a combustion zone comprising, in combination with a kiln having a combustion zone, an enclosure communicating at one end with the kiln, a sleeve extending through the opposite end of the enclosure into the interior thereof, means supporting the sleeve for angular adjustment within the enclosure, an air pipe supported within the sleeve for angular adjustment as a unit therewith and extending therebeyond into the enclosure a fuel feed pipe of less diameter than said air pipe spacedly supported within the latter for angular adjustment as a unit therewith, and adapted to inject fuel into the combustion zone.
7. Fuel feed mechanism for discharging fuel into a combustion zone comprising, in combination, a combustion zone, a fuel feed pipe adapted to direct fuel into the combustion zone, an enclosure surrounding the discharge end portion of the fuel feed pipe and communicating at one end with the combustion zone, means for directing highly heated air into the enclosure including means for heating the air thus directed, an air pipe communicating with a source of relatively cool air having an internal diameter greater than the external diameter of the feed pipe and telescoping that portion of the feed pipe within the enclosure providing an annular air passage there-

around to shield the fuel feed pipe from direct contact with the highly heated air in the enclosure, said fuel pipe and air pipe being approximately coextensive in length within said enclosure, and means for axially shifting one of said pipes relative to the other to position the end of one pipe either short of or beyond the end of the other pipe.

8. Fuel feed mechanism for discharging fuel into a combustion zone comprising, in combination, a combustion zone, a fuel feed pipe adapted to direct fuel into the combustion zone, an enclosure surrounding the discharge end portion of the fuel feed pipe and communicating at one end with the combustion zone, means for directing highly heated air into the enclosure including means for heating the air thus directed, an air pipe communicating with a source of relatively cool air having an internal diameter greater than the external diameter of the feed pipe and telescoping that portion of the feed pipe within the enclosure providing an annular air passage there-around to shield the fuel feed pipe from direct contact with the highly heated air in the enclosure, said air pipe being mounted for axial adjustment relative to said fuel feed pipe, and means for axially adjusting said air pipe to vary the position of the end of the air pipe either short of or beyond the discharge end of the fuel feed pipe.

HARRY S. LEE.
